UNITED STATES PATENT OFFICE

EDWIN COWLES, OF SHORT HILLS, NEW JERSEY, ASSIGNOR TO COWLES ENGINEERING CORPORATION, OF SEWAREN, NEW JERSEY, A CORPORATION OF NEW JERSEY

PUMP

Application filed October 14, 1927. Serial No. 226,093.

This invention relates to pumps which are used to pump fluid in which may be entrained fibrous material such as lint, for example.

5 It has been found that if fibrous material is permitted to pass through a pump, the strands sometimes collect on the impeller in sufficient quantity to interfere seriously with the proper functioning of the pump. It is 10 an object of the present invention to provide means to cooperate with the impeller in such manner as to free the same of any fibers which may collect thereon.

15 Other objects and advantages of the invention will appear hereinafter.

A preferred embodiment of the invention selected for purposes of illustration is shown in the accompanying drawings, in which,

20 Figure 1 is a vertical section on the line 1—1 of Figure 2.

Figure 2 is a horizontal section on the line 2—2 of Figure 1.

Figure 3 is a side elevation of the impeller.

25 Referring to the drawings, a pump of the centrifugal type has been selected to illustrate the invention, in which the casing 1 is provided with an inlet opening 2 and an outlet or discharge opening 3. Mounted for 30 rotation within the said casing 1 is an impeller wheel 4 having blades 5 therein.

In using this type of pump for pumping fluid in which fibrous materials are entrained, as, for example, in pumping liquid 35 to produce agitation in fabric washing machines, it is found that the loose fibrous strands which are entrained in the liquid tend to collect on the impeller, and particularly on the forward ends 6 of the blades 40 in such manner that a wad of fibers sometimes collects which interferes with the proper operation of the pump.

According to the present invention it is 45 proposed to provide means which shall frictionally engage such fibrous materials so as to cut or wipe them from the points where they are lodged. In the preferred embodiment illustrated the said means comprises a wire 7 which may be secured at one end 50 to the inside of the intake passage, and which

may extend upwardly so that its free end 8 extends into the area within which the fluid is received by the impeller, and in close proximity to the ends 6 of the blades. If desired, the end 8 may be arranged to contact with 55 the blades, although for most purposes it is sufficient for the two to be mounted in close proximity.

Preferably the wire 7 is made of resilient material, such as steel, in order that it may bend upon engagement with a fibrous mass but may spring back into place after the mass has moved by. If desired, the wire 60 may be flattened or sharpened at its upper end to provide a knife edge, although for 65 most purposes a round wire such as disclosed in the drawings is sufficient.

In operation, the impeller 4 is driven 70 through the shaft 4' in the usual manner to cause fluid to be forced out through the discharge opening 3 and drawn in through intake opening 2. Any fibrous material which 75 is entrained in the fluid which tends to engage the impeller blades is immediately engaged by the wire 7 and either pulled loose or cut away thereby. In certain instances the material may be merely wiped off by the wire, or in other cases the strands may actually be severed by the repeated friction of the wire against the fibrous mass as the 80 impeller rotates. For convenience in description, both of the foregoing actions are intended to be included within the term 85 "cutting" as used herein.

It will be understood that the invention 85 may be variously modified and embodied within the scope of the subjoined claims.

I claim as my invention:

1. A pump comprising a casing having inlet and outlet openings, an impeller, and 90 resilient means cooperating with said impeller to rub and cut by abrasive action fibrous material entering the pump through said inlet opening.

2. A pump comprising a casing having inlet and outlet openings, an impeller, and 95 resilient means having an end extending into the area where the fluid passes from said intake into said impeller to rub and cut by 100

abrasive action fibrous material entering the pump through said inlet opening.

3. A pump comprising a casing having inlet and outlet openings, an impeller, and a resilient member having one end secured to said casing within said inlet opening, and having its other end extending into close proximity with said impeller to rub and cut by abrasive action fibrous material entering the pump through said inlet opening.

10 In testimony whereof, I have signed my name to this specification this tenth day of October.

EDWIN COWLES.
